(57) CLAIM

The ornamental design for a strap, as shown and described.

DESCRIPTION

FIG. 1 is a perspective view of a strap;

FIG. 2 is a bottom plan view of the strap of FIG. 1;

FIG. 3 is a top plan view of the strap of FIG. 1;

FIG. 4 is a left side view of the strap of FIG. 1;

FIG. 5 is a right side view of the strap of FIG. 1;

FIG. 6 is a front view of the strap of FIG. 1, the rear view appearing the same; and,

FIG. 7 is a perspective view of another exemplary embodiment of the strap of FIG. 1.

In the drawings, the broken lines in FIG. 7 depict a seat back and form no part of the claimed design.
